Conrad C. Stremme

CONRAD C. STREMME, OF AUSTIN, TEXAS.

Letters Patent No. 88,527, dated March 30, 1869.

IMPROVEMENT IN HAT-VENTILATORS.

The Schedule referred to in these Letters Patent and making part of the same.

To all whom it may concern:

Be it known that I, CONRAD C. STREMME, of Austin, in the county of Travis, in the State of Texas, have invented a new and improved Mode of Ventilating Hats, Bonnets, Caps, &c., of all styles and fashions; and I do hereby declare that the following is a full and exact description thereof, reference being had to the annexed drawings, making a part of this specification, in which

Figure 1 is a perspective view to the inside of a hat, showing the ventilating-apparatus at *f*.

Figure 2, a vertical longitudinal section of the same hat.

Figure 3, a perspective view of a bonnet, with ventilating-cushion *g*, showing its working-apparatus at *f*.

Figure 4, the same bonnet, in a vertical longitudinal section.

Figure 5, a part of the ventilating-apparatus in full size, and in different states of construction, marked A B C.

Figure 6, a cross-section, in full size, of a parallelopipedic stick, for forming the spiral required in the construction of the ventilating-apparatus.

Figures 7, 8, and 9, representing vertical sections of oriental ventilating-hats, are only to demonstrate their peculiar construction, and the forms necessarily resulting therefrom.

The nature of my invention consists in providing the inside of the head-coverings, at the point of contact with the head, with a lining of an elastic spiral formed into a cushion, through which the air can freely circulate around the whole head.

To enable others to make use of my invention, I will proceed to describe its construction and operation.

As material for my ventilating-apparatus, I use a flat wire, or a similarly-shaped piece of whalebone, rattan, vulcanized India rubber, wood, cane, &c. After having it made flexible, either by dry heat, steam, hot or cold water, according to its nature, I wind it, in this state, around a parallelopipedic stick, and let it cool or dry, as required, after which it retains its form when removed therefrom. In regard to its lightness, elasticity, color, and cheapness, I prefer the rattan for all head-coverings made of straw; the more so, as a simple soaking, even in cold water, makes it sufficiently flexible.

Having formed the elastic spiral, as represented by A, fig. 5, I sew this either directly to the inside of the head-covering, with the proper intervals between the windings, as is shown by *f* in figs. 1 and 2, or, more conveniently, to single straw or other bands, as represented in B, fig. 5, so that the ends unite to a regular ring, when intended for hats and caps, or a horse-shoe-shaped cushion, *g*, figs. 3 and 4, when intended for bon-

nets, which ring or cushion may then be further provided with a proper lining, as shown in figs. 3 and 4 at *g*, made and sold separately from the head-coverings, and sewed into or attached to the hat by the user or vender.

To make the intervals between the different windings of the thread, without any trouble, equal to each other, I perform the sewing of the same, either to single bands or the head-coverings themselves, through slits *d*, fig. 5, C, correctly arranged in a metallic pattern, *e*, held in place by a provisional sewing through the holes *c*.

The advantages which common head-coverings that are provided with this simple ventilating-apparatus have over those not so provided, are the following:

First, they do not communicate, to the head of the wearer, the heat they receive from the sunbeams to which they may be exposed, as they are separated from the head by the ventilating-apparatus.

Secondly, they allow the air to circulate freely around the whole head, keeping it cool by carrying off all heated vapors that arise from perspiration, which otherwise would accumulate and become oppressive, causing headache and sun-stroke.

Thirdly, they last longer, as they are not liable to become unpleasant from being penetrated by hair-grease, and compensate, thus, considerably more than in full for the small additional cost.

In adaptation to the purpose, they compare favorably with the oriental ventilating-hats, as is obvious to the eye. They are, in many other respects, superior to them, as the following remark will demonstrate. The oriental hat is invariably stiff and inflexible, in consequence of the material preferred, and the peculiar construction adopted, which has unavoidably led to such fixed forms as figs. 7, 8, and 9, in vertical sections represented. These new-improved head-coverings, on the other hand, are pliable, more independent in regard to material, of simpler construction, and adaptable to any form that fashion may demand.

I lay no claim to those oriental ventilating-hats, and the principle upon which their construction is based; but

What I do claim as my invention, and desire to secure by Letters Patent, is—

The elastic ventilating-device, consisting of a spirally-wound flat wire, or similarly-shaped strip of whalebone, rattan, &c., adapted to be attached to head-coverings, substantially as herein described.

CONRAD C. STREMME.
